ELECTRICAL THERMOSTAT

Arthur J. Kercher, Berkeley, Calif.

Application July 19, 1935, Serial No. 32,183

3 Claims. (Cl. 200—137)

This invention relates generally to apparatus for controlling flow of electric current in accordance with the temperature of a fluid or other heated body. It has particular application to electrically heated appliances, such as electric ovens or electric water heaters, where it is desired to interrupt current supply when the temperature of the heated air or water reaches a predetermined value, or where maintenance of a predetermined temperature level is required.

It is an object of the invention to provide an apparatus of the above character which will be simple and reliable in operation, and which will serve to control relatively heavy current loads.

Another object of the invention is to provide an apparatus of the above character which will make use of elements having different temperature coefficients of expansion, which will be so coordinated as to afford ample relative movement for a given temperature change to operate contacting mechanism, but which will not necessitate the use of thermostatic elements of undue length.

Additional objects of the invention will appear from the following description in which the preferred embodiments of the invention have been set forth in detail in conjunction with the accompanying drawings.

Referring to the drawings:

Fig. 1 is a side elevational view, partly in cross-section, illustrating apparatus incorporating the present invention, the particular form illustrated being combined with elements of an electric water heater.

Fig. 2 is a side elevational detail of certain of the operating parts as shown in Fig. 1, but showing different operating positions.

Fig. 3 is a sectional end view of the apparatus as shown in Fig. 1, the section being indicated by the line 3—3 of Fig. 1.

Fig. 4 is a cross-sectional detail, taken along the line 4—4 of Fig. 1.

Fig. 5 is a side elevational view, partly in cross-section and showing a modification of the invention suitable for use in conjunction with an electric oven.

Fig. 6 is a cross-sectional detail taken along the line 6—6 of Fig. 5.

Fig. 7 is a diagrammatic view, illustrating typical electrical circuit connections.

Referring first to Figs. 1 to 4 inclusive, the apparatus illustrated includes a mounting designated generally at 10, which may vary as to detail but which in this instance includes a pair of spaced metal plates 11 and 12. Since in the

form shown, the apparatus is intended primarily for use with electric hot water heaters, the mounting serves to carry a plurality of electrical heating elements 13 of the immersion type, together with a thermostatic operating unit 14. 5 The elements 13 can be of the type disclosed and claimed in Patent No. 1,671,592, granted May 29, 1928. Briefly, each element 13 consists of a tubular metal sheath 16, having its opposite sides provided with longitudinal creases 17, to provide 10 two passages for accommodating an electrical resistance conductor 18. The electrical resistance conductor in this instance is coiled or convoluted, and is disposed within beads or tubes 19 of suitable refractory insulating material. One end of 15 each of the tubes 16 extends through a member 20, to which the plates 11 and 12 are secured, and which becomes a part of the general mounting. The free ends of the tubes 16 are sealed by closure caps or plates 21. As disclosed in said Patent No. 1,671,592 the creases 17 terminate short 20 of the closure 21, thus affording a lateral passage-way through which the conductor 18 and its tubular insulation 19 may extend.

The thermostatic operating unit 14 preferably 25 includes a tubular metal case 22, which is formed similar to the sheath 16 for the heating elements 13. One end of this casing likewise extends through member 20 of the mounting, while the free end is sealed by closure cap 23. 30

Extending longitudinally within the passages 24, afforded within the casing 22, are the rods 25 and 26. These rods are preferably made of a metal or metal alloy having a negligible temperature coefficient of expansion, as for example 35 invar. On the other hand casing 22 is made of a metal or metal alloy having a substantial temperature coefficient of expansion, as for example nichrome, copper or bronze. Within the closed end of casing 22, there is a rocker 27, 40 having a pivotal mounting 28 to the supporting bracket 29. The adjacent ends of rods 25 and 26 have spherical shaped end portions 31 which are adapted to seat in spherical shaped sockets 32, provided in the arms of the rocker. The 45 other ends of rods 25 and 26 are shown projecting from the casing 22. Where a terminal block 33 may be provided for making electrical connection to the heating elements 13, openings 34 can be provided through which the rods are accommodated.

One of the rods 25 and 26 and in this instance rod 26, is operatively connected to contacting mechanism designated generally at 36. The other rod 25 is engaged by abutment means carried by 55

the mounting 10, and which can be constructed as follows:—

A plunger 37 is aligned with rod 25, and is slidably disposed within a sleeve 38. Sleeve 38 is in turn threaded into a member 39, which extends between the two plates 11 and 12 and is secured thereto. One end of the sleeve carries a hand adjustment lever 41, by means of which the sleeve can be turned and advanced or retracted with respect to the mounting. Plunger 37 carries a head 43, which is provided with spherical shaped socket 44 to accommodate the spherical shaped end portion 46 of rod 25. A compression spring 47 has its one end seated upon the head 43, and its other end seated upon the adjacent end of sleeve 38. The outer end of plunger 37 is provided with some suitable form of limiting shoulder, as for example, it can be threaded to accommodate the lock nuts 48. It is apparent that the abutment means described serves to apply force to rod 25 against the rocker 21, by virtue of the compression spring 47. The magnitude of this force and the positioning of sleeve 38, can be varied by changing the setting of lever 41.

The contacting mechanism may be a simple set of electrical contacts adapted to be opened and closed by relative movement between the outer end of rod 26 and the mounting 10. However, for handling relatively heavy current loads, a more elaborate type of contacting mechanism is desirable, in order to avoid arcing. The mechanism illustrated is of the relay type, and includes a magnetic core 51, one leg of which is provided with the winding 52. Near the poles of the core 51 there is a magnetic armature 53, carried by pivot pin 54. Armature 53 carries a movable contact 56, adapted to cooperate with a stationary contact 57. While various expedients can be utilized for attaching contact 56 to the armature 53, the arrangement illustrated utilizes a block 58 of insulating material, mounted upon the armature 53. Overlying the upper face of block 58, there is a metal strip 59, which carries the contact 56. A threaded pin 61 is mounted on block 58, and extends loosely through the metal strip 59. A light compression spring 62 presses down upon strip 59, and has its upper end seated upon an adjustable nut 63. Metal strip 59 also carries a depending stud 64, which extends loosely into a recess 66 provided in block 58. Thus when armature 53 is pulled downwardly by coil 52, a certain amount of lost motion is provided between the insulating block 58 and the metal strip 59, so that contacts 56 and 57 are resiliently urged together by spring 62. A suitable spring 67 can be provided for lifting the armature 53, and thus causing the contacts 56 and 57 to open, when the core 51 is deenergized.

In addition to the armature 53 there is a lever 68, which is carried by a pivot pin 69. Immediately below pivot pin 68 the lever is provided with a spherical shaped socket 71, in which the adjacent end portion 72 of rod 26 is seated. As viewed in Fig. 1, lever 68 is urged to turn in a clockwise direction about the pivot pin 69, by a leaf spring 73. Lever 68 carries a movable electrical contact 74, which is adapted to cooperate with a stationary contact 76. Contacts 57 and 76 are directly electrically connected with each other, as illustrated.

As representative of suitable arrangement for supporting the contacts 74 on lever 68, this contact is shown carried by a threaded stud 77, which in turn is adjustably carried by one end of a metal

strip 78. Metal strip 78 is carried by an insulating block 79, which is a part of lever 68.

In order to afford an interlock between lever 68 and armature 53, the lever carries an upward extending spring tongue 81, the upper end of which is shaped to form a latch 82. Swinging of tongue 81 in one direction is limited by a relatively rigid portion 83 of the lever 68. Latch 82 is adapted to engage a dog 84, formed upon the free end of armature 53.

Mounted on the lever 68, adjacent the open leg 85 of core 51, there is a magnetic armature 86. The adjacent core leg 85 is slotted to accommodate a shading coil 87.

The typical circuit connections shown in Fig. 7, can be briefly explained as follows:—One side of the current supply line 1 is shown connected to terminal of the electrical heating unit 13a. The other current supply line 2 is connected to the stationary contacts 57 and 76. One terminal of relay winding 52 is connected to contact 74, and the other to the other terminal of the heating unit 13a. The heating units also connect to the movable contact 56, whereby when contacts 56 and 57 are closed, the heating units are connected directly across the current supply.

Operation of the apparatus described above, can now be explained as follows:—Assuming operation with a hot water heater, the heating units 13, as well as the casing 22 of the thermostat operating means, extend into a water tank, or into a chamber through which water to be heated is being circulated. Lever 41 is set in accordance with the temperature at which it is desired to interrupt the flow of current, as for example 180°. While the lever 68 is latched with respect to armature 53, the main contacts 56 and 57 are closed, and current is supplied to the electrical heating units. Likewise at such time the relay winding 52 is short circuited, and no current flow occurs through the same. Lever 68 is held in closed position by virtue of the pressure of spring 47, which is transmitted through rod 25, rocker 21, and rod 26. As the temperature of water surrounding casing 22 increases, heating of this casing causes it to expand longitudinally, while the rods 25 and 26 do not expand. Thus if plunger 37 were fixed, relative movement would occur between the closed end of the casing 22 and the corresponding end of rod 25, to cause rotation of the rocker 21 in a counter-clockwise direction, as viewed in Fig. 1, and such relative movement would be transmitted to rod 26. However since rod 26 would likewise remain of fixed length, the relative movement between the end portion 72 of rod 26 and the mounting 10, would amount to substantially twice the change in length of casing 22, by virtue of thermal expansion. Since plunger 37 is resiliently urged against rod 25 by compression spring 47, it may initially move somewhat relative to the mounting as the temperature increases, until lock nuts 48 engage the outer end of sleeve 38. Further expansion of casing 22 causes relative movement between the end portion 72 of rod 26 and the pivot pin 69, thereby causing lever 68 to swing towards open position, to open contacts 74 and 76, and to displace the latch 82 with respect to dog 84. Armature 53 now snaps to open position under the urge of spring 67, to open the main contacts 56 and 57, and to interrupt supply of current to the heating units. Full open positions of the levers 68 and 53, are shown in Fig. 2. When the casing 22 has cooled a sufficient amount, its contraction

causes relative movement between the end portion 72 of rod 26 and the pivot pin 69, thereby causing lever 68 to swing towards closed position, to close contacts 74 and 76, and to displace the latch 82 with respect to dog 84. Armature 53 now snaps to closed position under the urge of spring 67, to close the main contacts 56 and 57, and to supply current to the heating units. Full closed positions of the levers 68 and 53, are shown in Fig. 3. When the casing 22 has cooled a sufficient amount, its contraction

causes lever 68 to swing in a counter-clockwise direction, as shown in Fig. 2. Such movement serves to close the contacts 74 and 76, which as will be evident from the circuit diagram of Fig. 7, connects the relay winding 52 across the current supply lines 1 and 2, in series with the heating units 13a. Magnetization of core 51 immediately causes armature 53 to snap to closed position, which again causes the latch 82 to engage the dog 84. For the short interval that core 51 is energized, the magnetic pull of core leg 85 upon armature 86, prevents vibrating movements of lever 68, and thus chattering of contacts 74 and 76 is prevented.

It is a simple matter to adjust the apparatus for different temperature level of operation, by changing the setting of lever 41. It will be noted that the type of abutment means utilized in conjunction with this lever, for pressing upon rods 25, avoids displacement of parts or possible breakage when the casing 22 is relatively cool. The multiplied motion secured by utilizing two rods 25 and 26 in a single expansible casing, makes it possible to avoid the use of casings of undue length, and at the same time makes possible accurate regulation at a desired temperature level. Likewise in the particular type of apparatus illustrated, in which heating units are grouped in close proximity to the casing 22, the water is caused to thermally circulate about the casing 22, and the casing 22 is heated to a temperature somewhat higher than the temperature of the main body of water being heated, so that it will in effect anticipate a desired temperature level, in interrupting the current supply. Furthermore, if for some reason water should be drained from the heater, the casing 22 will be heated by radiation from the units 13, and by hot currents of air, so that under such conditions it will interrupt the current supply before the heating units are permanently injured by an unduly high temperature.

The modification illustrated in Figs. 5 and 6 is similar to that previously described with reference to Figs. 1 to 4 inclusive, except that it is intended particularly for use with electrical ovens, such as are employed on domestic cooking ranges. In such applications the casing 22a is arranged to extend into the oven compartment, preferably in relatively close proximity with the heating elements. The outer surface of casing 22a is shown provided with scarf lines or grooves 91, in order to afford a greater exposed area, and thereby increase heat transfer with respect to the surrounding air. A modified form of abutment means for engaging the rod 25, is also illustrated, and is constructed as follows:—An L 92 is carried by pivot pin 93, and has its one arm provided with a socket 94, in which the end portion 46 of rod 25 is seated. The other arm 96 of lever 92 is forked and is connected to one end of a tension spring 97. A rod 98 is threaded into a member 99, which in turn is carried by the two plates 11 and 12 of the mounting. A collar 101 is formed on rod 98, and one face of this collar bears upon the raised portions 102 of arm 96.

It is evident that the type of abutment means described with respect to Figs. 5 and 6, operates in substantially the same manner as the abutment means disclosed in Figs. 1 to 4 inclusive. When the apparatus has been set for operation at elevated temperatures, as for example, between 205 and 500° F., collar 101 will be spaced from the portions 102, when the casing 22a is cold.

I claim:

1. In an electrical thermostat, a mounting, an elongated tubular casing having one end of the same secured to said mounting, the other end of said casing being closed, said casing being formed of metal having a substantial temperature coefficient of expansion, a pair of metal rods extending longitudinally through said casing in parallel relationship, a rocker pivotally mounted in a closed end of said casing and having its arms connected to corresponding ends of said rod, both said rods being made of metal having negligible temperature coefficient of expansion, contacting means actuated by relative movement between the other end of one of the rods and said mounting, and means for adjusting the temperature level of operation of said contacting means, said last means including an adjustable abutment carried by the mounting and engaging that end of the other rod removed from said rocker, said last means including a movable abutment engaging that end of the other rod remote from the rocker, a spring serving to urge said abutment against its associated rod, and adjustable means serving to limit movement of the abutment in one direction.

2. In a thermostatic device, a mounting, an elongated casing having one end of the same secured to said mounting and being formed of material having a substantial temperature coefficient of expansion, that end of the casing remote from said mounting being closed, a rocker pivotally connected to said casing within said closed end, a pair of rods extending longitudinally within said casing, said rods being formed of a material having a negligible temperature coefficient of expansion, connections between the corresponding ends of said rods and the arms of said rocker, adjustable abutment means for the other end of one of the rods, said abutment means normally serving to limit the longitudinal movement of said one rod in a direction towards said mounting, but permitting movement in an opposite direction, a spring associated with the abutment means and against which the abutment means may yield when said one rod is moved relative to the mounting beyond said limit, and response means actuated by relative movement between the mounting and the other end of the second rod, said last means including a movable member engaging the second rod, and a second spring for urging said last named member in a direction to urge the second rod towards said rocker, said second spring being incapable of supplying sufficient force to effectively overcome the force of the first named spring.

3. In a thermostatic device, a mounting, an elongated casing having one end of the same secured to said mounting and being formed of material having a substantial temperature coefficient of expansion, that end of the casing remote from said mounting being closed, a rocker pivotally mounted within said casing at a point remote from said mounting, a pair of rods extending longitudinally within said casing, said rods being formed of a material having a negligible temperature coefficient of expansion, connections between the corresponding ends of said rods and the arms of said rocker, adjustable abutment means for the other end of one of the rods, said abutment means normally serving to limit movement of the one rod in a direction toward the mounting but permitting movement in an opposite direction, a spring associated with the abutment means and against which the abutment

means may yield, and response means actuated by relative movement between the mounting and the other end of the second rod, said last means including a lever pivotally carried by the mounting and capable of limited oscillating movement, one arm of said lever having abutting engagement with the adjacent end of the second rod, and a spring serving to urge said lever in a di-

rection to force said arm against said second rod, the force thus exerted by said second named spring being normally applied against the force of the first-named spring but being incapable of overcoming the force exerted by the first named spring.

ARTHUR J. KERCHER.
